UNITED STATES PATENT OFFICE.

JAMES LEWIS, OF GERMAN FLATS, NEW YORK.

IMPROVEMENT IN SWITCHES FOR TELEGRAPHS.

Specification forming part of Letters Patent No. 40,346, dated October 20, 1863.

To all whom it may concern:

Be it known that I, JAMES LEWIS, of Mohawk, in the town of German Flats, county of Herkimer, and State of New York, have invented a new and useful apparatus which may be used as a switch in electric telegraph-offices in connection with the wires and instruments of the electric telegraph.

The use of my invention is intended to facilitate the operations of telegraphing by enabling the operator to dispense in a great measure (though not necessarily entirely) with the use of a considerable number of switches as ordinarily used, and to relieve him greatly from the uncertainties which attend the accidental displacement of the ordinary switch.

I propose to call my invention "Lewis' Permutating-Switch" for telegraph-offices; and I do hereby declare that the following is a full, clear, and exact description of the construction and operation of said permutating-switch, reference being had to the annexed drawings, making a part of this specification, in which—

Figure 1 is a front elevation of the apparatus complete. Fig. 2 is an elevation of the upper surface of part 33 of Fig. 1, separated therefrom, and divested of some of its attachments. Fig. 3 is a section of Fig. 2. Fig. 4, exhibits parts 5 6 7 8 of Fig. 1, disconnected from Fig. 2. Fig. 5 is a diagram of the cylindrical surface of 5, Fig. 4, with its projections. Fig. 6 is a modification of the third section of Fig. 5. Fig. 7 exhibits a lateral view of the parts projecting from the cylinder 5 of Fig. 4, the same being shown in elevation in Fig. 5. Fig. 8 is an end view of the cylinder 5 of Fig. 4, with the projecting parts thereof removed. Fig. 9 is a modified construction of the parts *a r n b h g h'* of Figs. 1, 2, 3, and 10. Fig. 10 is a rear elevation of the case with the back removed, and the parts 4 5 6 7 8 of Fig. 1 disconnected, showing the relations of the remaining parts to each other.

Similar parts of the figures are referred to by similar letters and numerals, so, likewise, are parts performing similar electrical functions identified by letters of the same name but of different character.

A suitable wooden case is provided, as shown in the outlines of Figs. 1 and 10, with a front plate, 1, Fig. 1, on which is marked a suitable

dial, an inclosure of suitable depth, a back plate, 2 2', Fig. 1, extending laterally on each side of the case or inclosure and perforated with screw-holes for fastening the apparatus to a wall or other permanent support. That part of the dial which is within the lettered portion is represented as cut out, showing the parts of the apparatus within the case back of the opening thus made.

On the top and bottom of the case are represented several screw-cups. Those on the top A B R N connect with four different telegraph-wires, radiating in different directions from the telegraph-office, for which the instrument under consideration may be supposed to be adapted. Those on the bottom of the case are intended to connect with the relay-instrument of the office at H H' and with the ground-plate at G, or, if necessary, a battery may be connected with G.

The parts visible through the dial are a base-board, 33, which supports the working parts of the apparatus; a metallic plate, 4, (with a triangular hole through it to permit parts beyond it to be seen,) fastened to the base-board 33 by two screws, the heads of which are seen in the drawings. The plate 4 supports the anterior extremity of the shaft of the cylinder or barrel 5, on which shaft as it projects through the dial is fixed an index, 6, which is held fast to said shaft by means of a nut, 7, or any other suitable device. To facilitate handling the index 6 a crank-knob, 8, may be added. Another plate similar to 4 supports the posterior end of the shaft of the barrel 5 in similar manner.

On the surface of the barrel 5 may be seen a number of projections, to which Roman numerals I to XVIII refer, having the same significance as in Figs. 4, 5, 6, and 8, as will be hereinafter explained.

On the upper surface of the base-board 33 are a number of metallic springs, *a r n b* and *h g h'*, only two of which, *a* and *h*, are visible in Fig. 1, as they all lie in the same plane. (See Fig. 2.) These springs are fastened to the base-board with screws 9 9. The ends of the springs near the screws are turned upwards at a right angle, as at 12 12, to afford points to which to fasten a wire or strip of metal to connect the several springs *a r n*, &c., with the screw-cups

A R N, &c. On the left a strip of metal is shown at a^* , where it connects the spring a with screw-cup A. On the right the connecting-strips $h^* g^* h^*$ pass down through holes in the base-board 3 3, (at 14 14 14, Figs. 2, 3, and 10) to the screw-cup H G H'. At the middle of the base-board 3 3 the springs $a r n$, &c., are bent to form a notch on the upper surface of each spring, with an inclined plane sloping away from the notch 13 on each side.

The projections on the surface of the barrel 5 fit into the notches 13 in the springs $a r n$, &c., at the point 13, and there make electrical contact. The notches 13 serve to hold the barrel 5 from turning, each spring $a r n$, &c., by its elasticity holding the notch 13 firmly to its corresponding projection on the barrel 5.

The several projections on the barrel 5 may be successively brought into the notches 13 by rotating the barrel 5 by applying the hand to the crank-knob 8.

The notches in the springs $a r n b h g h'$ are in a line, as shown by the dotted lines 13 13, Figs. 2 and 3, and the line thus formed is parallel with the axis of the barrel 5 and below the barrel 5, as seen in Fig. 1 at 13.

At the ends of the springs $a r n$, &c., are provisions for preventing them from coming in contact with the cylindrical surface of the barrel 5 when the barrel is turned so that any of the springs are not acted upon by the projections on the barrel. The end of each spring has a short slot cut in it, as shown at 11. (Appendage of Fig. 2.) This slot 11 is made to embrace a narrow nail, 10, Figs. 1, 2, 3, and 10, made for the purpose, which nail has a hook projecting on one side to catch on the upper surface of the spring. These nails are driven into the base-board 3 3 far enough to confine the springs $a r n$, &c., within proper limits, and permit the springs $a r n$, &c., to press with their full force against the projections on the barrel 5 when the said projections are turned into the notches 13. The nails 10 also prevent the springs $a r n$, &c., from being accidentally displaced laterally.

The notches 13 in the springs $a r n$, &c., in Figs. 1, 3, and 10, are represented as formed in the metal by beating between suitable dies. They may, however, be formed in a separate piece of metal, which may subsequently be attached to the springs, as shown at 13, Fig. 9.

The springs $a r n$, &c., are intended to act as conductors of electricity, and are required to possess considerable elasticity. They may therefore be of brass, that being the most economical material that will serve as a good conductor and possess the requisite stiffness.

The local order of the springs $a r n$, &c., on the dotted lines 13 13, Fig. 2, reading from front to rear, is $a h r g n h' b$. They are arranged alternately, as shown in Fig. 2, so that one end of each spring may be wide enough to let a screw through into the base-board 3 3 without bringing them in contact with each other, whereby insulation would be destroyed.

Part 5, Figs. 1 and 4, is a cylinder of wood or other suitable non-conductor of electricity, having sufficient firmness of structure to insure its durability. This cylinder has a number of slots or channels cut in its surface, of equal depth and at equal distances apart, parallel with each other and the axis of the cylinder, for the reception of several pieces of brass or other suitable metal of the forms shown at 15 16 17 18 19 20 in Figs. 5 and 7. The unshaded parts in Fig. 5 correspond to the projections on the barrel 5, Fig. 4, and to the projections on the right of the several parts 15 16 17 18 19 20 in Figs. 7, and are contact-surfaces.

The pieces of metal that project from the surface of the barrel 5 in Figs. 1 and 4 are intended to serve as connecting-bars between two or more of the springs $a r n$, &c. A portion of one side of each (between the ends) is cut out, so that no contacts will be made by the connecting-bar other than those intended.

It is not important that all the connecting-bars have a portion of one side cut out. Those which are designed to make contact with two contiguous springs, as a and h' , Fig. 2, may be of the form of the part 15', Fig. 7.

The arrangement of most of the connecting-bars 15 to 20 in the barrel 5 is of the simple character shown in the first two sections of Fig. 5—i.e., end to end in the slot provided for them. Instances are presented at XV and XVII, Fig. 5, where the connecting-bars lap by each other. In those instances the slots in the barrel 5 will have to be suitably enlarged, the bars so bent that when a strip of suitable insulating material is placed between them and they are fastened in the barrel their several projections will be in line with each other and parallel with the axis of the barrel 5. (See as illustrations XV and XVII, Figs. 4 and 5, and XIII and XIV, Fig. 6.) The projections on the surface of the barrel 5 being brought into contact with the springs $a r n$, &c., by rotating the barrel 5, the friction between the surfaces thus brought in contact tends to keep them bright, so as to perfect electrical connection at each contact.

The several connecting-bars or projections may be secured in their places in the barrel 5 by means of any suitable cements, or by means of wedges or pins.

The several screw-cups on the top and bottom of the case that incloses the apparatus are connected with the several springs $a r n$, &c., within the case, as shown in Fig. 10, by the parts $a^* r^* n^* b^*$ above, and parts $h^* g^* h^*$, below the base-board 3, letters of the same name referring to parts connected continuously.

Instruments of the character here shown will be unlike each other in the following several particulars: in the number of the springs $a r n$, &c., which will be determined by the number of wires and instruments of a telegraph-office connected therewith; in the size of the barrel 5, and in the number and arrangement of its projecting parts, which will be deter-

mined by the number of wires (or springs *a r n*, &c.) used, and the number and variety of changes to be made thereon. These conditions will in all cases determine the construction of an instrument and its variations from the apparatus used in illustration.

There are numerous circumstances in which it might be supposed to be necessary or desirable to use one or more ordinary switches in connection with this apparatus. As some or most of the instances will suggest themselves, it is unnecessary to particularize. Circumstances can also be conceived under which it might be desirable to combine two or more instruments as one for the purpose of securing a greater number of changes than could readily be made in one instrument. The equivalent of this may be suggested—*i. e.*, the construction of an apparatus with two or more sets of springs, *a r n*, &c., and two or more barrels, 5, combined as one instrument, and inclosed in one case, with suitable dials, &c.

For the purpose of enabling particular lines to work continuously through the apparatus—as, for instance, from A to B, on the instrument—the two springs *a* and *b* may be electrically connected with each other by means of a bar of metal that will make contact with those springs at the end near the hook-headed nail 10, when the springs are not pressed down by the projections on the barrel 5. This, however, is merely an accessory part which may or may not be used, and does not affect the value of the parts which constitute the prominent features of this invention. Again, the bar of metal which is proposed to be used to connect two springs, as above, may be in two parts, each of which may connect with the ends of the helix of a sounder or relay, so that the operator may at all times be signalled.

As the conditions under which this permutating-switch is to be operated must determine the number and arrangement of some of its parts, conditions will now be suggested according to which the special apparatus here-with presented to illustrate the construction and operation of this invention has been constructed, from which the construction required by other conditions may be inferred and understood.

Let it be supposed that the apparatus illustrating this invention had been constructed to answer the following conditions, *viz.*, to be located in a telegraph-office at Herkimer, where, condition 1, it is to work in connection with the office-relay, and, condition 2, be also connected with a ground-plate; condition 3, to be connected with telegraph-wires from the following places, *viz.*, first, Albany, second Buffalo, third Richfield, fourth Newport; condition 4, that it shall be able to make the following separate connections through the office-relay, *viz.*, first, Albany and Buffalo, second Albany and Richfield, third Albany and Newport, fourth Buffalo and Newport, fifth Buffalo

and Richfield; condition 5, to make the same connections and leave out the relay; condition 6, to connect Herkimer alone with each of the above-named places or lines singly; condition 7, to work all the lines at once: thus, to connect, first, Albany and Buffalo, at the same time Richfield and Newport; second, Albany and Richfield, at the same time Buffalo and Newport; third, Albany and Newport, at the same time Buffalo and Richfield; fourth, Albany, Herkimer, and Buffalo, at the same time Richfield and Newport.

The first condition is established by the screw-cups H H', connected with the two ends of the wire of the office-relay helix. The second condition connects ground-plate with screw-cup G. The third condition connects screw-cups A with Albany, B with Buffalo, R with Richfield, and N with Newport. The fourth condition is shown to be complied with in the first section of the diagram, Fig. 5, and by reference from that to Figs. 4 and 1. Similar references to Figs. 1 and 4 follow the remaining conditions. The fifth condition is complied with in the second section of Fig. 5. The sixth condition is complied with in the third section of Fig. 5. The seventh condition is complied with in the fourth section of Fig. 5. This will be more decidedly apparent when the letters on the dial and screw-cups are regarded as initials of the several places named, and the same significance is attached to letters of the same name on Figs. 2 and 5. Their relations are such as are here indicated.

Operation: The diagram Fig. 5 is the key to the operation of the instrument; and in constructing an apparatus of similar character, but to operate under different conditions, a similar but somewhat different diagram would be required as a chart of the barrel 5. Let it be supposed that the apparatus is set up at Herkimer, and that it is in working order, and that the operator wishes to communicate with Albany without interruption, he turns the index on the dial to the center of the division marked A H. This is the eleventh division on the dial, and refers to the corresponding part of diagram Fig. 5, where it will be seen that a connecting-bar connects *a*, Albany, with *h*, one end of the helix-wire of the office-relay. Another connecting-bar connects *h'*, the other end of the helix-wire of the office-relay, with *g*, the ground-plate. On the instrument it would be seen that a short connecting-bar made contact with springs *a* and *h*, and that another connecting-bar made contact with springs *h'* and *g*, the explanation of which is, that when the circuit is closed under these conditions the battery-current passes through the spring *a*; thence through a connecting-bar to the spring *h*; thence through the relay back to spring *h'*; thence through a connecting-bar to the spring *g* to the ground, the rest of the circuit being through the earth to the battery at Albany. This explanation of one instance in

which the apparatus is used readily suggests the explanations which any other changes on the instrument would require.

One figure of the annexed drawings remains unexplained, and it has been reserved to be presented here.

Fig. 6 is a modification of the third section of Fig. 5. It will be observed in the third section of Fig. 5 that two of the connecting-bars convey a current, say, from h to g , while other two convey a current from h' to g . Allowing g to be practically the negative pole of a battery, the current passes through the relay at XI and XII in a contrary direction from what it does at XIII and XIV. If it be desirable to have the current of electricity pass through the relay or sounder attached to the screw-cups H H' always in one direction, (supposing g to be always negative, which, however, may not be invariably the case,) XIII and XIV in Fig. 5 may be arranged as shown in Fig. 6, where all the connections of g are with h' .

It may now be apparent that the several springs $a r n$, &c., as arranged in this apparatus, are practically so many terminations of electrical conductors; and that the several bars (1 to XVIII, or 15 16 17 18 19 20) serve to form connections between said springs; and that the said bars, being variously and suitably arranged on the surface of a cylinder, 5, may be made to make any desired connections between two or more of said springs, as may have been previously provided for; and that any of the connections provided for in the cylinder or barrel 5 and its connecting-bars I to XVIII, and their adaptations to the springs $a r n$, &c., may be readily made simply by turning said barrel by means of a crank or index provided for that purpose, a suitable dial on the front of the case inclosing the apparatus serving to determine to what point the crank or index shall be turned in order to effect any desired connection. It may also be apparent that if such an apparatus be adapted to the conditions of, and properly connected with the wires and apparatus of, an electric telegraph, it may be made to answer the purpose of a large num-

ber of switches, (as ordinarily constructed and used,) this being the designed object, purpose, and use of this invention.

I claim—

1. The barrel or cylinder 5, Figs. 1, 4, and 8, and its connecting-bars I to XVIII, (as many as may be necessary,) or their combined equivalent, when arranged to operate against springs $a r n$, &c., or their equivalents, substantially in the manner and for the purpose hereinbefore set forth.

2. The springs $a r n$, &c., Figs. 1, 2, 3, and 10, or their equivalents, (as many as may be necessary,) when arranged to act against a barrel, 5, and its connecting-bars I to XVIII, or their combined equivalents, substantially in the manner and for the purpose hereinbefore set forth.

3. The alternate arrangement of the springs $a h r g n h' b$ as shown in Fig. 2, when used for the purpose substantially as set forth.

4. The notches 13, with the inclined surfaces each side thereof on the springs $a r n$, &c., Figs. 1, 2, 3, 9, and 10, when arranged and used substantially in the manner and for the purpose set forth.

5. The mode described of limiting the upward movement and of preventing the lateral movement of the springs $a r n$, &c., by means of the slot 11 in the end of each spring and the hook-headed nail 10, in connection therewith, or their equivalent, when used substantially in the manner and for the purpose set forth.

6. The combination and use of (first) the barrel 5 and its connecting-bars I to XVIII, or their combined equivalent, with (second) the springs $a r n$, &c., or their equivalents, for the purpose substantially as set forth, together with (third) a suitable dial and index for making said barrel, connecting-bars, and springs, or their combined equivalent, practically available for the purpose set forth.

JAMES LEWIS.

In presence of—

S. E. COE,
JONAS SCHELL.
